UNITED STATES PATENT OFFICE

2,028,521

ELECTRIC SIGN CONTROLLER

Frank C. Reilly, New York, N. Y.

Application July 29, 1932, Serial No. 626,192

1 Claim. (Cl. 74—242.15)

This invention relates to control mechanism of the type covered by Patent 1,451,112, April 10, 1923, wherein a "talking sign" effect is attained by a perforated strip controlling a bank of contacts connected with the lamps or light units of the sign.

Special objects of the invention are to improve the mechanism for handling the travelling tape or record strip, so as to insure the same running straight and true and under proper tension; to simplify and facilitate the threading of the record strip through the machine and to better the machine generally in various practical respects.

These objects and others are attained by certain novel features of construction, combinations and relations of parts as hereinafter illustrated and broadly claimed.

The drawings accompanying and forming part of this specification illustrate certain embodiments of the invention, but it will be realized that the actual physical structure may be modified as regards this particular illustration, all within the true and broad intent of the claim.

Fig. 1 is a side elevation of one practical embodiment of the invention.

Fig. 1a is a detail of the equalizer or "bridle" construction.

Fig. 2 is a top plan view of the machine.

Figs. 3 and 4 are enlarged cross-sectional detail views as on lines 3—3 and 4—4 of Fig. 1.

Fig. 5 is a broken fragmentary detail illustrating construction and operation of the circuit controlling contacts.

In Fig. 1, the control tape or strip is shown at 1, laced back and forth between the upper fixed rolls 8 and the lower movable set of rolls 9 and extending from the lower edge guiding and positioning roller 10, up through the contact bank at 11 to the driving roll 12, which as indicated in Fig. 2, operates from motor 13 through suitable reduction gearing 14.

The movable set of rolls are shown as carried by a frame 15, hinged at one end at 16 and connected at its opposite end at 17, with an endless belt or sprocket chain 18, arranged vertically on upper and lower sprockets 19, 20, the upper being adapted to be turned from a hand wheel 21, through worm gearing or other suitable gearing 22.

By means of this hand wheel control, the lower roller frame may be either raised or lowered and be held supported by the sprocket chain or by the runs of tape, or partly by both. In Fig. 1, the roller frame is shown hung from the loops of record tape and hence tensioning the tape by its

entire weight. This condition may be varied at will. Thus by turning the hand wheel in one direction, the chain may be utilized to lift the frame so as to wholly or partially relieve the tape of the weight of the frame and by turning the handle in the opposite direction, the chain may be used to pull down on the frame and hence add a positive force to the tensioning of the tape. The worm gearing is desirable both for the accuracy of adjustment and for the self-locking feature.

For convenience in threading the records, the lower rolls are shown pivoted at one side of the frame as indicated at 23, Fig. 4, as in the patent above referred to, but in the present form of machine, the free ends of the shafts 24 carrying the rollers are held in the open sockets 25 in the side of the frame by an overstanding guard in the form of a bar 26, sliding over the top of the frame and movably and adjustably held by thumb screws 27 received through open slots 28 in the inner side of the bar. At the ends, this bar is shown as slidably held to the frame by the pins or studs 29 received in the closed slots 30, the latter limiting the outward opening movement of the sliding guard, preventing its separation from the frame and assuring proper support of the same while the rollers are being adjusted.

It is important both that the tensioning rolls be at the proper height and be accurately leveled, so as to keep the strip from tracking to one side or the other. Accordingly, vertical adjustment of the pivoted end of the tensioning frame is provided by mounting the pivot shaft or stud 16 in a bracket member 31, designed to seat inside the corner angles 32 of the supporting frame and cooperating with a bracket member 33, engaging outside the corner angles to constitute a clamp adjustably held in the selected position on the supporting frame by the clamp bolts 34. Relative angular adjustment of these two clamp members is made possible by providing enlarged bolt openings 35 in the outer clamp part and means for effecting such adjustment is present in the disclosure in the form of a hand screw 36, threaded in a lug 37 on one end of the clamp part 31 and engaging an outstanding lug 38 on the corresponding end of the other clamp part 33. It will be apparent, that by somewhat loosening one or more of the bolts 34 which secure the clamp parts on the supporting frame, the two clamp parts may be relatively shifted or twisted by adjustment of hand screw 36 to rock the tensioning frame transversely to cause the strip to track properly.

The lower guide roll 10 is shown supported by

a similar adjustable clamp construction, the corresponding parts being similarly numbered in Figs. 1 and 4. This guide roll is shown as having flanges 39 serving as edge gages for the strip and it will be evident that by adjusting the mounting of the roll vertically and transversely after the manner described in connection with the tensioning frame, this roll may be made to direct the strip straight and true up through the contact bank.

The lower guide roll is shown as seated in open bearings 40 in its supporting bracket 41 and as removably held therein by the pivoted latches or dogs 42, which when thrown back permit this roll to be lifted out of its bearings.

To cause the strip to run straight and free through the control box, the back plate 43 which is opposed to and cooperates with the spring contacts 44 is shown as pivotally hung at 45, on the supporting bars 46, Fig. 3, so that it may rock on these vertical pivots and hence adjust itself to the strip passing over the face of the same and to the contacts bearing against said strips.

The board may be locked in the position of such adjustment as by means of the positioning studs 47, engaged with opposite edge portions of the same and secured in adjusted relation on the base of the contact bank by lock nuts 48.

To facilitate the placing of the strip in the control box, the back plate 43 is mounted so that it may be swung to an open position as by the construction shown in Figs. 1 and 3, where the bars 46 are illustrated as hinged at 49 each at one end and as caught at the opposite end by thumb screw 50 on a swinging toggle link 51. It will be evident that upon loosening thumb screws 50, thus releasing the toggle links 51, the back board or panel 43 may be swung open to uncover the bank of contacts and open up this portion of the apparatus to freely receive the strip.

The contacts are of special design as shown in Fig. 5, comprising spring brushes 44 set in the ends of tubular mounts 52, held in an insulating panel 53 and separated in rows at their terminal ends by strips of insulation 54. These strips aid in holding apart the wires which are entered in the openings 55 and held by the screws 56 in the ends of the brush tubes.

The perforated strip is held to the feed roll 12 by a spring tensioned pressure roll 57, Figs. 1 and 2, mounted in a bracket 58 carried by the studs 59, sliding in a stationary supporting bracket 60. Springs 61 engaged on these studs and bearing against the supporting frame thrust the

pressure roll against the strip extending about the feed roll. Retraction of this pressure roll is effected in the illustration by a handle 62, pivoted on the central one of the studs 59, against a stop shoulder 63, Fig. 2, and having a lug 64, 5 riding over a stationary cam 65. In the position illustrated, with the lug engaged with the low part of the cam, the roller is thrust forward by the springs to hold the strip engaged in driven relation with the feed roll. By rotating this lever 10 so as to carry the lug over the incline of the cam, it will be evident that the pressure roll will be drawn back away from the feed roll to permit placing the strip about this roll.

The feed roll may be rubber-faced to frictionally engage the tape. At times it is desirable to remove and replace this feed roll. To make this operation easy, the outer bearing 66 for the feed roll is shown as removably secured at 67 to the end of the supporting bracket 68.

For detecting breakage of the record strip, a roll 69 is shown in Figs. 1 and 2 pivoted on the frame at 70 in position to bear against the upwardly running stretch of the tape and having an outwardly projecting arm 71, carrying a contact 72 for engagement with a relatively stationary contact 73. These contacts may be connected with a relay or be otherwise connected to effect the stopping of the machine in case of breakage of the strip. This detector roll is placed between the feed roll and the contact bank at a position where the drag is heaviest and breakage most likely to occur in case of weakness of the strip.

The drive roller is located directly above the switch bank, making the machine compact as to design. The adjustment of the guide roll at the foot of the contact bank or switch box, together with the adjustability of the roll carrying frame, makes it possible to accurately line up the tape and keep it running straight and true without 40 any side weave.

To equalize the pull on the roll carrying frame, the chain 18 may be connected to the ring 75 attached by links 76 to the end of the frame as indicated in Figs. 1 and 1a.

What is claimed is:

In a machine of the character disclosed, a roll carrying frame pivotally supported at one end, an equalizing bridle attached to the opposite end of said pivoted roll carrying frame and a flexible 50 connection engaged with said bridle for raising and lowering said end of the frame.

FRANK C. REILLY.
